[57]**CLAIM**

The ornamental design for a plate rack, as shown and described.

DESCRIPTION

FIG. 1 is a front, top and side perspective view of a first embodiment of a plate rack, showing my new design; FIG. 2 is a front elevational view thereof;

FIG. 3 is a right, side, elevational view thereof, the left side elevational view being a mirror image;

FIG. 4 is a top plan view thereof;

FIG. 5 is a rear elevational view thereof;

FIG. 6 is a bottom plan view thereof;

FIG. 7 is a front, top and side perspective view of a second embodiment of a plate rack, in accordance with my new design showing a three plate-mounting style, additional views of this rack being similar to the corresponding views of the first embodiment except for the number of plate mountings; and,

FIG. 8 is a front, top and side perspective view of a third embodiment of a plate rack, in accordance with my new design showing a four plate-mounting style, additional views of this rack being similar to the corresponding views of the first embodiment except for the number of plate mountings.
